UNITED STATES PATENT OFFICE.

HARVEY E. BARDEN, OF GRANVILLE, NEW YORK.

DESIGN FOR A MEAT-KNIFE, &c.

SPECIFICATION forming part of Design No. 28,186, dated January 18, 1898.

Application filed December 3, 1897. Serial No. 660,709. Term of patent 14 years.

To all whom it may concern:

Be it known that I, HARVEY E. BARDEN, a citizen of the United States, and a resident of Granville, in the county of Washington and State of New York, have invented and produced a new and original Design for a Meat-Knife, Cleaver, and Tenderer, of which the following is a specification, reference being had to the accompanying drawings, forming part thereof.

Figure 1 is a side elevation of a meat-knife, cleaver, and tenderer, showing my new design. Fig. 2 is a sectional view taken on the line $x-x$ of Fig. 1.

As shown in the drawings, the leading or material feature of my design consists of a toothed edge A, extending from the front point of the blade rearwardly and outwardly and meeting the cleaver edge B at an angle. The long curved edge C is the usual knife-edge.

The value of the angle between the tenderer edge and the cleaver edge is apparent and is one of the most important features of my design in that each edge is distinct.

The blade is made of double-beveled steel, shaped as shown in Fig. 2, and is provided with the usual hole D, Fig. 1, for suspending it when not in use.

Having described my invention, what I claim as new, and desire to secure by Letters Patent, is—

The design for a meat-knife, cleaver and tenderer as herein shown and described.

Signed at Granville, in the county of Washington and State of New York, this 29th day of November, A. D. 1897.

HARVEY E. BARDEN.
